No. 11,841

July 6, 1880

UNITED STATES PATENT OFFICE.

ALEXANDER S. MANN, OF ST. LOUIS, MISSOURI.

DESIGN FOR A RAILROAD BULLETIN-BOARD.

SPECIFICATION forming part of **Design No. 11,841, dated July 6, 1880.**

Application filed June 5, 1880. Term of patent 3½ years.

To all whom it may concern:

Be it known that I, ALEX. S. MANN, residing at the city of St. Louis, in the State of Missouri, have invented a new and original Design for Railroad Bulletin-Boards, of which the following is a specification.

My design consists in a board for railway signs or posters, as shown in the accompanying photograph, which is a front elevation.

10 The leading feature of my design consists in a board carrying at top a model of a locomotive, B, standing on a flat base, C, beneath which is a circular frame, D. At each side of the sign the board has rounded ornamental 15 extensions E, and below them is curved orna-

mentally, as shown at F. Below the sign D is a box, A A, and at the lower part is a rectangular case, G. The face is ornamented with design in relief, as plainly shown in the accompanying photograph.

20

I claim as my design—

The railway bulletin-board having the representation of a locomotive, B, at top, sign-frame D, case G, box A, and raised fancy-work, substantially as shown and described.

ALEXANDER S. MANN.
